UNITED STATES PATENT OFFICE.

MAX HERSKOVITZ, OF CHICAGO, ILLINOIS, ASSIGNOR TO PEERLESS LIGHT COMPANY, OF CHICAGO, ILLINOIS, A CORPORATION OF ILLINOIS.

LIGHTING-FIXTURE.

1,226,211.

Specification of Letters Patent. Patented May 15, 1917.

Application filed July 26, 1916. Serial No. 111,436.

To all whom it may concern:

Be it known that I, MAX HERSKOVITZ, a citizen of the United States, and a resident of Chicago, county of Cook, and State of Illinois, have invented certain new and useful Improvements in Lighting-Fixtures, of which the following is declared to be a full, clear, and exact description.

This invention relates to lighting fixtures, and has reference more particularly to pendant stems or wall brackets. Heretofore pendant stems and wall brackets of the type described in this specification have been constructed of many pieces, which necessarily increased the cost of manufacture, because of the time required in assemblage, and because of the work to be done on each individual part of the device. The primary object of this invention is to provide for a simple assemblage of parts which may be made very cheaply and which may be readily attached to the support. Another object is to provide a single piece insertible body portion adapted to be secured to the support, and surrounded by a thin metal sleeve, which sleeve may be finished or decorated in any desired manner, thus providing a lighting fixture which shall have a handsome appearance, and yet its cost of construction is extremely low as compared with its appearance. Another object is to provide an insertible body portion complete in itself, which may be sold to the trade as an article of merchandise ready to be covered by a shell or cover. With these and other objects in view, this invention consists in the several novel features of construction, arrangement and combination of parts hereinafter fully set forth and claimed.

The invention is clearly illustrated in the drawing accompanying this specification, in which:

Figure 1, is a view partly in side elevation and partly in central vertical section through a lighting fixture embodying a simple form of the present invention; Figs. 2, 3, and 4, are side views of the supporting fixture disassembled; Fig. 5, is a side view of the main body portion of the device; Fig. 6, is a central longitudinal section of a wall bracket form of the fixture showing the invention applied thereto; Fig. 7, is a cross-section taken on the line 7—7 of Fig. 6; Fig. 8, is a side elevation of a modified form

of the invention, and Fig. 9 is a side elevation of a ring seen in Figs. 1, 6 and 7.

Referring first to Figs. 1 to 5, inclusive, 10, designates a supporting member here shown as comprising a crowfoot supporting device, which is secured to the ceiling or wall of a room as the case may be, and in accordance with the usual practice, said supporting member is formed with an internally or externally screw-threaded ring 11, upon which is screwed the threaded end of 65 the fixture.

In its preferred form the device comprises an insertible body portion 12, having screw-threaded extensions 13, 14, on its ends; said extensions are illustrated in the form of externally screw-threaded necks, the neck 13, being adapted to be screwed into the internally screw-threaded ring 11, of the crowfoot support 10. A lengthwise extending groove 15, is formed in one side 75 of the body portion 12, for the reception of the conductor cords α , of the lighting fixture and said groove extends throughout the greater portion of the length of the body portion 12. The neck 14, has a passageway 16, formed therein through which the conductor cords extend out from the grooved body portion to the light socket or sockets. Said body portion comprises two integral parts 17, 18, the part 17, being of greater 85 diameter than the part 18, to leave a shoulder 19; said shoulder forms an abutment place for a thin shell of tubular material 20, which shell may be highly finished and polished to correspond with the finish of 90 the other fixtures of the room and may be constructed of brass or of other materials which will take a high finish and polish. Said tubular member 20, and part 17, of the body portion 12, of the device, may be 95 of substantially the same diameter so that the device may pass through the opening in the canopy (seen at 21,) while the device is in an assembled condition. The canopy is held on the device by a set screw 22, in the usual, common and well-known manner.

The tubular member 20, extends from the shoulder portion 19, to the end of the part 18, of the body portion, and is held in place thereon by suitable means, here shown as 105 comprising a ring or loop 23, having a flanged portion 24, adapted to bear against the adjacent end of the tubular member 20.

The flanged end 24, has an internally screw-threaded opening whereby the ring may be screwed upon the neck 14. I may form a groove 28^a, in the body portion at the shoulder 19, for the reception of a split ring 28, which ring closes the gap between the sides of the groove 15, at said shoulder. One end 29, of the ring may be bent inward toward the center of the ring and inserted in an aperture 30, formed in the body portion. This construction prevents accidental turning of the ring. The ring is preferably round in cross-section to provide a smooth surface, thus preventing any chafing of the conductor cords at the place where they emerge from the upper end of the shell 20.

One of the particular advantages of this device consists in the fact that it may be assembled quickly and with very little labor, and that the device, with the shell or tubular portion omitted, may be sold to the trade as an article of merchandise. This permits the dealer or person installing the device, to employ shells or tubular members of the desired finish, and said shells may be applied to the body portion by first unscrewing the ring or loop 23, inserting the part 18, through the shell and screwing the ring back upon the neck 14, thereby clamping the shell between the shoulder 19, and flange 24, of the loop or ring 23. In wiring the device the conductor cords may be pushed through the passageway of the device when fully assembled, and when disassembled may be passed through the ring 23, shell 20, opening 16, in the neck 14, and laid in the groove 15; the parts may then be assembled. When assembled the conductor cords project out through the portion of the groove above the shell and may be fastened to the house wires.

When used as a wall bracket, as shown in Fig. 6, a ball 25, or other ornamental knob or ornament may be screwed upon the hollow neck 14, to give the end of the device an ornamental appearance, and an electric lamp socket 26, may be screwed into a transversely extending, internally threaded hole 27, which is formed in the wall of the part 18, near the end bearing the neck 14. In this instance the external shell 20, is also provided with an opening in its side through which projects the threaded neck of the electric light socket. In wiring the form illustrated in Fig. 6, the device is disassembled, the wire passed through the aperture 27, and laid in the groove, after which the device is assembled. It is to be noted that the groove in the body portion 12, is made quite wide and deep so as to facilitate the insertion of the conductor cords through the device.

In the form shown in Fig. 8, the shell or tubular member 20, is held in place by a split ring 23^a, the ends of which extend

through apertures in the shell and into apertures in the lower end of the body portion. In this case the neck 14 is omitted.

The insertible body 12, may be made of cast metal or it may be struck up from sheet metal as desired, thus the cost of construction may be materially reduced.

More or less variation of the exact details of construction is possible without departing from the spirit of this invention, and I desire therefore, not to limit myself to the particular form of the invention shown and described, but intend to point out in the following claims all of the invention disclosed herein.

I claim as new and desire to secure by Letters Patent:

1. A new article of manufacture, comprising an insertible body portion, U-shaped in cross section throughout the greater portion of its length and having a screw-threaded neck on one end, said body portion being adapted to be inserted in an inclosing shell, and the groove in the body portion being adapted for the reception of conductor cords.

2. A lighting fixture comprising an insertible body portion having a screw-threaded neck at each end, a shell surrounding said body portion, and means for securing said shell on said insertible body portion, there being a passageway within the shell for the reception of conductor cords.

3. A lighting fixture member, comprising an insertible body portion having a screw-threaded extension on one end, and a reduced body portion for the reception of a shell, there being a shoulder formed between the unreduced portion and the reduced portion against which a shell may bear, and there being a passageway for conductor cords extending lengthwise of the body portion, and means for securing a shell on said reduced portion in contact with said shoulder.

4. A lighting fixture member, comprising an insertible body portion having a screw-threaded extension at each end, and having a reduced body portion for the reception of a shell, there being a shoulder formed between the unreduced portion and reduced portion against which a shell may bear, and there being a passageway for conductor cords extending lengthwise throughout the greater extent of the body and opening out through the body portion at the threaded extension on the reduced portion thereof, and a member threaded on the threaded extension of the reduced portion and arranged to hold a shell in engagement with said shoulder.

5. A lighting fixture member, comprising an insertible body portion, having a screw-threaded neck on each end, and having a reduced body portion for the reception of a

shell, there being a shoulder formed between the unreduced portion and reduced portion, against which a shell may bear, and there being a groove extending lengthwise of the body and lying on each side of said shoulder, and a screw-threaded member threaded on the screw-threaded neck of the reduced portion for holding a shell in contact with said shoulder.

16 6. A lighting fixture member, comprising an insertible body portion, having a screw-threaded neck at each end, one of which is arranged for attachment to a screw-threaded support, said body portion having a reduced portion, which leaves a shoulder at the unreduced portion, there being a lengthwise extending groove formed in the side of the reduced and unreduced portion, said groove opening out through the neck at the 20 end of the reduced portion, a shell surrounding said reduced portion and abutting against said shoulder, and a fixture sup-

porting member having an internally screw-threaded part screwed upon said last mentioned neck and abutting against said shell. 25

7. A lighting fixture member, comprising a lengthwise grooved insertible body portion having a screw-threaded extension at each end, one of which is arranged for attachment to a screw-threaded support, said body portion having a reduced portion between its ends leaving a shoulder, there being an annular groove at said shoulder, a split ring in said groove, and overhanging the lengthwise extending groove, a shell 35 surrounding said reduced portion and abutting against said shoulder, the ring underlying said end of the shell, and a screw-threaded clamping member screwed upon the threaded extension on the reduced portion and abutting against the end of the shell. 40

MAX HERSKOVITZ.
